UNITED STATES PATENT OFFICE.

FRANKLIN H. ELWELL, OF CHICAGO, ILLINOIS.

OIL CUP.

Application filed June 24, 1921. Serial No. 480,038.

To all whom it may concern:

Be it known that I, FRANKLIN H. ELWELL, a citizen of the United States, residing at Chicago, in the county of Cook and State of Illinois, have invented certain new and useful Improvements in Oil Cups, of which the following is a description.

My invention relates to that general class of devices known as oil cups, and has for one 10 of its objects to provide an oil cup which shall in normal operation continually and constantly feed oil to the parts desired with the usual gravitational flow, and which is so designed that the seating of the closure 15 cap thereof will cause a temporary force feed instead of the gravitational flow, which force feed will cease after said cap has been substantially seated and permit the gravitational feed to continue to act.

20 The invention has among its other objects the production of a device of the kind described that is simple, convenient, durable, compact, efficient, dependable and satisfactory for use wherever found applicable.

25 Many other objects and advantages of the device herein shown and described will be obvious to those skilled in the art to which this invention appertains.

To this end my invention consists in the 30 novel construction, arrangement and combination of parts herein shown and described, and more particularly pointed out in the claims.

In the drawings, wherein like reference 35 characters designate like or similar parts throughout the views,

Fig. 1 is a vertical section through my device;

Fig. 2 is a similar vertical section of 40 another form or modification of my invention;

Fig. 3 is a section taken substantially on the line 3—3 of Fig. 2;

Fig. 4 is a section taken substantially on 45 the line 4—4 of Fig. 2;

Fig. 5 is a section taken substantially on the line 5—5 of Fig. 1; and

Fig. 6 is a section taken substantially on 50 the line 6—6 of Fig. 1.

In the drawings, wherein I have illustrated a preferred embodiment of my invention, 1 designates the casing or reservoir of my oil cup, said casing having a threaded lower end 2 for attachment to any suitable 55 part to be lubricated or to any connection leading thereto.

The oil chamber 3 has an outlet opening 4 at the lower end thereof, and an inlet opening 16 at the upper end thereof, both said upper and lower ends being preferably reduced in diameter and externally threaded as shown, said externally threaded inlet end 5 being adapted to receive a cooperating closure cap 12, said closure cap being internally threaded at 13, and projecting within the chamber 3 centrally thereof. In alignment with the inlet and outlet openings thereof is a sleeve 6, seated at its lower end 9 at the base of the casing and having apertures or openings 7 through the side wall 70 thereof so arranged as to communicate with the chamber 3, whereby oil may flow from said chamber through said openings and out through said outlet 4.

In order to regulate the amount of oil flow through the apertures 7, I have arranged a packing 8 of any suitable compressible absorbent or porous material, such as felt or any other equivalent for the purpose, between the casing and the openings 7. 80 The upper end of the sleeve 6 in the preferred construction does not extend entirely to the upper wall of the casing, but is spaced therefrom or stopped short thereof.

It will be understood that the casing 1 and sleeve 6 may be made in one or more parts in any manner desirable or preferred. The cap 12 has a centrally projecting plunger part 10, preferably hollow, and with a closed lower end 11, said plunger 90 being adapted to slide in the inlet opening in the sleeve 6 so as to act as a piston or plunger, the sleeve 6 together with the inlet bore of the casing serving as a guide or cylinder therefor. A vent 15 formed 95 through the wall of the plunger 10 communicates with the hollow interior thereof and with the atmosphere through a second vent 14 in the cap so that when the cap is fully seated, as shown in Fig. 1, the air 100 pressure from the atmosphere will be communicated through the vents 14 and 15 to the body of oil in the chamber 3, thus preventing air locking and permitting its gravity feed through the apertures 7 and 105 out through the discharge outlet 4. From the positioning of the vent 15 it will be seen that as the cap with its inwardly projecting plunger 10 is initially positioned in the inlet to the filled chamber 3, the subsequent 110 screwing down or tightening of the cap will cause the plunger to act as a piston to

exert pressure upon and force the lubricant in the central duct 6 out through said outlet 4, the vents during the initial seating of the cap being inoperative to permit the atmosphere to act upon the oil in the chamber 3 or the oil to flow out or be forced out through the vents. The continued tightening or seating of the cap 12 substantially to its complete seating will cause the vents 14—15 to become operative, as shown in the drawings, thereby terminating said force feed and permitting the atmospheric pressure to act upon the lubricant within the chamber and the gravitational feed to become operative through the apertures 7 and the outlet 4.

In the modification shown in Figs. 2, 3 and 4, the casing is threaded at its lower end 22 and is shown as attached to pipe L 20. The chamber 23 has an inlet and outlet opening 25 and 24 respectively in axial alignment with each other as shown, the inlet end 25 being annularly reduced, as shown. As in the previous modification, 25 there is a central sleeve 6 within the chamber, the upper end of said sleeve being spaced from the top of said casing, said sleeve having apertures 7 adjacent the lower end thereof and there preferably being a compressible, absorbent material 8, or its equivalent, between said sleeve and the casing, said sleeve bearing on and seating in the casing at its lower end 9. The cap 27 in this instance is not screw-threaded, but 35 is adapted to be pressed down in place over the end of the casing 21, said cap having an annular peripheral wall 28 having one or more inwardly offset portions 31 adapted to engage in cooperating detents 30 formed in the peripheral wall of the casing 21 to 40 securely latch and hold the cap in position. Projecting inwardly centrally of the cap 27 is a plunger part 26, similar to the plunger 10 in the previous modification described, 45 said plunger being either integral with the cap or secured thereto by soldering, brazing, or in any other equivalent manner, said plunger having a closed lower end 11 and a vent opening 15 through the side wall 50 thereof for the same purpose as previously described. Communicating with the vent 15 is a vent 32, in the upper portion of the cap 27, the atmospheric pressure being communicated thereto through the kerfs 29, or 55 the equivalent, formed in the peripheral wall 28, the chamber 33 therebetween serving to exclude dust, dirt or other foreign matter from said vent.

As previously described, the oil chamber 60 23 and the sleeve 6 is filled with oil and as the cap is being seated the vents 15—32—29 are inoperative and prevent the oil being forced out through the vents, the plunger 26 acting as a piston to force feed the oil 65 through the outlet of the oil cup until the

cap has been substantially completely seated, whereupon said vents will become operative to permit the oil in said chamber to flow by gravity through said outlet.

It will be particularly noticed that when 70 the plunger is withdrawn for the purpose of re-filling the device, withdrawal of the plunger will tend to create a vacuum in the plunger chamber below the plunger, and consequently, if there is any oil remaining 75 in the chamber 3, the vacuum will tend to pull or suck the oil through the ports 7, thereby tending to clear the device and positively draw out any oil into the chamber 80 below the plunger. This is particularly desirable in case the oil becomes thick or of such consistency that it does not flow easily 85 through the packing 8. The device may be said to substantially consist of a casing provided with a gravity feed chamber and a force feed chamber. The force feed chamber may be termed the "internal chamber" 95 with a plunger adapted to operate in the force feed or internal chamber.

Having thus described my invention, it 90 is obvious that various immaterial modifications may be made in the same without departing from the spirit of my invention; hence I do not wish to be understood as 95 limiting myself to the exact form, arrangement, construction and combination of parts herein shown and described, or uses mentioned.

What I claim as new and desire to secure 100 by Letters Patent is:

1. In an oil cup of the kind described having a lubricant chamber with an inlet and an outlet, a cap for said inlet and adapted to extend into said chamber, a vent near the upper end of said cap communicating with the atmosphere and normally inoperative, said vent being so positioned that it operatively communicates with said oil chamber only after said cap has been substantially 105 fully seated, said seating of the cap forcing the oil in said chamber through said outlet.

2. An oil cup having an oil chamber therein, a plunger cap movable in said oil chamber and having a vent adjacent the upper end thereof, said vent being normally inoperative and adapted to be uncovered only when the cap is substantially fully seated, whereby said cap will act as a piston to force oil through said outlet until said vent is uncovered and operative, whereupon said vent 115 will communicate with said oil chamber to permit gravity flow therethrough.

3. An oil cup having an oil chamber therein, a cap therefor and fitting thereinto to form a plunger, an opening at the upper end of said cap communicating with the atmosphere and with the oil chamber only after the cap has been fully seated, whereby the seating of the cap will cause the plunger to initially exert a pressure on the oil in the 125 130

chamber, forcing it through said outlet, and ceasing to exert said pressure after it has been seated.

4. An oil cup, comprising an inner and outer oil chamber and having an inlet and outlet therefrom, closure means for the inlet to said cup, said closure means engageable within said chambers to exert a pressure on the oil therein, a vent, and means in said cap 10 normally inoperative and communicating with said oil chambers only when said cap has been substantially fully seated.

5. An oil cup comprising an inner and outer oil chamber and having an inlet and outlet therefrom, a plunger adapted to fit within said inner oil chamber so as to exert pressure on the oil therein, a cap for said inlet and controlling said plunger, and vent means in said plunger normally inoperative 20 and communicating with said oil chambers only when said cap has been substantially fully seated.

6. An oil cup comprising an inner and outer oil chamber and having an inlet and outlet therefrom, a closure means for said cup, said closure means having a centrally-extending plunger part adapted to fit within said inner oil chamber so as to exert pressure on the oil therein, and vent means in said 30 plunger through said cap normally inoperative and communicating with said oil chambers only when said cap has been substantially fully seated.

7. An oil cup having a lubricant chamber, a sleeve within said chamber and forming a second lubricant chamber, the upper end of said sleeve being spaced from the top of said oil cup, apertures through said sleeve at its lower end and communicating with the outer 40 chamber to permit oil to flow therethrough to the outlet thereof, a cap for closing said inlet to the oil chambers, a plunger carried by said cap and slidably within said inner chamber, said plunger having a vent therein 45 adjacent its upper end and communicating with the atmosphere and the oil chambers only when said cap has been substantially fully seated, whereby the seating of said cap will cause said vent to be normally inoperative and cause the plunger to exert a pressure

on the oil in the inner chamber, forcing it through said outlet.

8. A combined gravity and force feed oil cup comprising a chambered casing having an inlet and outlet at opposite ends thereof, 55 said casing adapted to receive oil therein, a hollow sleeve positioned within said chamber and communicating with said outlet, the upper end of said sleeve being spaced from the upper end of said casing, said sleeve having an aperture near its lower end communicating with said chamber, a cap for closing the inlet opening and extending into said sleeve, said cap having a closed lower end whereby the seating of said cap will force 60 the oil in said sleeve through said outlet, a vent adjacent the upper end of said cap normally inoperative and operative only when the cap has been substantially completely seated, whereupon the oil in said chamber 65 will flow by gravity through the aperture at the lower end of said sleeve from the outer chamber and through said outlet, and absorbent means between said apertured end of the sleeve and the casing whereby the gravitational flow therethrough may be adjustably regulated. 70

9. In an oil cup of the kind described, a gravity feed oil chamber having an inlet and outlet, a force feed oil chamber arranged therein intermediate said inlet and outlet, and a plunger for said force feed chamber, said plunger being operable only while said inlet is being closed. 80

10. In an oil cup of the kind described, a gravity feed lubricant chamber with a lubricant inlet and an outlet, a force feed chamber within said gravity feed chamber, a plunger operable within said force feed chamber, and a cap for said inlet and controlling said plunger, whereby said plunger is operable 90 only while the cap is being seated.

In testimony whereof, I have hereunto signed my name in the presence of two subscribing witnesses.

FRANKLIN H. ELWELL.
